UNITED STATES PATENT OFFICE

2,423,146

MACHINE FOR FILLING AND OTHERWISE
PREPARING ENVELOPES FOR POSTStanley Charles Herbert, Nunhead,
London S. E. 15, EnglandOriginal application April 25, 1939, Serial No.
269,923. Divided and this application Decem-
ber 15, 1942, Serial No. 469,129

14 Claims. (Cl. 93—6)

1

This invention is a modification of the invention described and claimed in the specification No. 2,318,073. The present invention was defined in the specification filed originally on the application, Serial No. 269,923, for Patent No. 2,318,073, but was withdrawn from the said application to form the subject-matter of the present application, which therefore bears the relation of a division to the said application, Serial No. 269,923. The present invention has among its objects to provide a construction of machine for filling the envelopes and tucking the flap without first reversing the flap upon the front of the envelope; to modify the construction and arrangement of the letter thruster mechanism; to modify the construction and mounting of the letter guide fingers; and to modify the assembly of the several mechanisms comprising the machine.

The invention is illustrated, by way of example, in the accompanying drawings.

Figure 1 is a diagrammatic sectional elevation of a construction of the apparatus according to the invention for operating upon envelopes having the flap extended into alignment with the front surface of the envelope.

Figure 2 is a sectional elevation, to a larger scale, of the mechanism at the envelope filling position.

Figures 3 and 3a together form an isometric view of the parts represented in Figure 2.

Figure 4 is an isometric view of the assembly of the envelope flap, clips or grippers and the envelope distending element, from the under side.

Figure 5 is an isometric view of a construction of the assembly of the letter guide fingers.

Figure 6 is a sectional elevation of the flap-tucking mechanism.

In carrying the invention into effect, by way of example, as applied to a machine in which the flap of the envelope is not reversed upon the front of the envelope before the filling operation, and as illustrated in Figures 1 to 5 of the accompanying drawings, the envelopes are fed from the magazine in the manner described in the specification No. 2,318,073, with the flap extended and foremost. A simple series of spaced pairs of feed rollers such as 86, 87, and guides, such as 91, 97, carry an envelope received from the magazine by the feed rollers 64, 65, 69 and 77 to the position at which the envelope is delivered to the filling mechanism. There is here disposed a fixed guide plate 117 of angular cross-section defining the junction of the path of approach of the empty envelope fed by the rollers 110 and 111 to the filling position and the path of despatch from the filling position of a charged envelope. The complementary guide plate 116 for the first path abuts upon the envelope receiving end of the filling table 121 and is there shaped to form an open channel in which the diverting member w

2

may move angularly about a horizontal pivotal axis immediately below the adjacent edge of the filling table 121. The diverting member w is formed as a plate extending transversely of the machine and of a width normal to the pivotal axis such that when it occupies the operative position under the action of a spring it substantially bridges the channel from the filling table 121 to the angular guide plate 117.

10 The filling table 121 forms a rearward continuation in a substantially horizontal direction of the complementary guide plate 116 and extends transversely in a middle position short of the side frames so as to leave a clearance space on each side. The rearward end of the filling table 121 is positioned at a distance from the foremost letter feed rollers 180, 182 such as to provide the space necessary to receive the table-like element 127 by which the flap of the envelope to be fitted is engaged when the said element is in the filling position. For this purpose the rearward part of the filling table is continued or formed as a bracket member of L-shaped or similar form that is supported from one of the transverse tie bars, 5, of the machine frame. In the transverse direction the filling table is of concave form or is provided with a depression or channel that is of the greatest depth at the rear edge of the table adjacent the said bracket member and that decreases in the forward direction until at the forward edge it has ceased to exist.

20 The mechanism for receiving the flap of the advancing envelope and carrying the envelope on to the filling table 121 is centered about a transversely disposed main spindle 123 below the filling table and comprises two supporting arms 124 pivotally mounted upon the spindle 123 in such relation that one of them may extend upwardly in each of the clearance spaces at the sides 30 of the filling table. They support the transverse table-like element 127 before referred to at such an angle to the length of the arms that when the arms are moved to bring the table-like element into the gap at the rear of the filling table the table-like element is aligned with the filling table. The table-like element has a transverse shape corresponding to that of the rear edge of the filling table. Thus it may have a shallow depression or channel at the middle of the width and may incline upwardly from the depression or channel to the lateral edges.

35 The clips or grippers 129 for engaging the flap of the envelope are of a transverse form such that while of sufficient width to engage the flap they may pass the angular edge of the back of the envelope. They are fixedly carried upon a spindle 138 mounted in the supporting arms 124 immediately below the outer or rear edge of the table-like element 127 and are of angular formation (see Figure 4) to permit them to extend out-

wardly from the spindle 138 over the edge and onto the surface of the table-like element 127. The spindle 138 also serves to carry at the middle the envelope distending element 146 which cooperates with the depression or channel of the table-like element 127 and is of a cross-sectional shape similar to that of the clips or grippers 129.

The clips or grippers 129 and the distending element 146 are operated in common by an operating arm 134 fixed to the spindle 138 and connected by a link 133 to a second arm 131 mounted upon a spindle 130 carried in the supporting arms 124 near the main spindle 123 by which the latter are carried, the latter spindle supporting a cam 139 adapted to act upon a roller 132 carried by the pivot of the link 133 and the second arm 131 when the spindle 123 is partially rotated at the appropriate time by the operating crank arm 140. A spring 134a conveniently acting upon the operating arm 134 tends always to move the clips or grippers 129 to the closed position.

The letter guide fingers 154 and 155 are also supported upon the table-like element 127 before referred to. For this purpose brackets 124a, provided as lateral extensions of the supporting arms 124 to the upper side of the table-like element 127, have pivoted to them on the studs *n* links *a* to which are pivoted levers *b* the fulcra of which are respectively provided upon a spindle *l* carried by plates or arms *c* pivoted by pivot *k* upon the supporting arms 124. The free ends of the levers *b* carry a transverse spindle *p* upon which the letter guide fingers 155, 154 are loosely mounted in spaced relation so that they respectively rest upon the clips or grippers 129 and the distending element 146. The plates or arms *c* are connected by rods *d* to arms *e* mounted fixedly upon the spindle 130. One of the arms *e* or an arm also carried by the spindle 130 supports a roller *f* which cooperates with a cam *g* mounted rotatably upon the main spindle 123 and operated by an arm *h*. Thus, the operative movement of the cam *g* causes the plates or arms *c* to move for the consequential lateral movement of the spindle *l* forming the fulcra of the levers *b* so that the levers are moved about their pivotal connections with the links *a* to advance or withdraw the letter guide fingers by moving the spindle *p*. The roller *f* may be caused to follow the cam *g* under the action of a spring, provided, for example, as a torsion spring upon the spindle 130. The brackets 124a upon the supporting arms 124 may carry, conveniently in a position substantially parallel with the table-like element 127, an upper letter guide plate 188 which when the table-like element 127 occupies the filling position comes to lie near to and cooperate with the most advanced pair of letter feed rollers 180, 182.

When the table-like element is in the position to receive the flap of an advancing envelope, as shown in Figure 1, it is inclined in the direction of the path of approach of the envelope and its lower or forward edge rests upon and depresses the diverting member *w* to permit the envelope to pass the latter.

The table-like element 127 and the parts carried by it may be balanced about the main spindle 123 by a counter-weight 124b which may conveniently extend transversely between the supporting arms 124. The required movements of the main spindle 123 and of the supporting arms 124 are effected from a suitable cam or cams through a rod 143, connecting the arm 125 of one of the supporting arms 124 with the arm 141

which is in fixed relation with the operating arm 144 upon the pivot pin 142.

Since the clips or grippers 129, the distending element 146 and the guide fingers 154, 155 are required to operate with envelopes having different forms of flap and of different widths, it is advantageous that they should be exchangeable for others of forms such that the particular envelope in use may be suited. Thus, the spindle 138 (Figure 4) upon which are mounted the clips or grippers 129 and the distending element 146 may be of square cross-section except for the turned ends forming the journals in the supporting arms 124. The angular ends of the clips or grippers 129 and of the distending element 146 may be bent at right angles so that they embrace the squared part of the spindle on two sides. The distending element 146 may be secured to the spindle in a mid position by means of a screw 146a. The clips or grippers 129 may have secured to them, as by welding, angle fittings 129a which form with the ends of the clips or grippers channels in which the spindle is received. The projecting parts of the ends and of the angle fittings may be recessed or notched for the engagement of locking plates 129b secured to the spindle by studs 129c extending through longitudinal slots 129d therein to permit movement of the locking plates 129b axially of the spindle, for engagement with or disengagement from the said recesses or notches. The location apart of the clips or grippers on the spindle is determined by the distending element and at the outer ends of the spindle by the operating arm 134 and a locating plate 138a respectively.

The letter guide fingers 154 and 155 may be provided with sleeves slidably to engage the spindle *p* upon which they are carried and may be maintained in spaced relation by distance sleeves 154a fixed to the spindle. They may thus be readily exchanged for others on removal of the spindle *p* from its bearings in the levers *b* carrying it. For this purpose the levers are provided with open bearing slots for the spindle and with correspondingly slotted pivoted closure fittings *b*¹ of channel form to embrace the spindle and the levers *b* and to be retained in the closed position, for example, by friction.

Since in the filling position of the envelope, the letter thruster mechanism is required to press forward the letter over the width of the flap before the letter enters the envelope, it is necessary that the arms 193 of the fork-like fittings 194 shall be of corresponding length and that they shall have a suitably extended travel. Accordingly, the letter register fitting is modified to permit the operative arms of such fittings to be disposed above the path of travel of the letters. For this purpose the fitting comprises a pair of lever arms 173 (Figure 2) positioned one at each side of the letter guide plates 170, 186, and fulcrummed at the rear ends to the inner frame plates 168. The said lever arms carry forward of the fulcra the movable feed rollers 175 of the first set of feed rollers 175, 176 and in a position above the guide plate 186 and at the forward ends a transverse tie bar 172 from which the letter registers proper extend downwardly to protrude through slots in the upper guide plate 186 when in the operative position. There is thus afforded increased clearance below the guide plate 170 for the movement of the fork-like fittings 194 and their arms 193.

The disposition of the table-like element 127 immediately in advance of the foremost pair of

letter feed rollers 180, 182, when in the filling position renders it advisable to modify the lower guide plates 177, 178, by foreshortening them to the proximity of the said feed rollers and supporting the lateral guide plates 178 by brackets 178a from the inner frame members and by mounting the middle guide plate 177 as a cantilever having support to the rear (Figure 3a).

Since the flap of the charged envelope leaving the filling position has not to be straightened the flap straightener may be replaced by simple guide plates 202a and 202b and the roller 204 may be mounted in a fixed position in contact with the roller 205.

Where, in the construction of a machine under consideration, the flap of the charged envelope has not to be turned from the position in contact with the front of the envelope, as illustrated in Figure 6 it is convenient to provide the flap tucking mechanism immediately after the feed rollers 111, 200 which receive the charged envelope when it is released by the clips or grippers 129. Thus the flap tucking mechanism is advantageously set so that the envelope is received in a substantially horizontal position, the feed rollers 204, 205, which deliver it to the flap tucking mechanism, being advantageously set close to the feed rollers 111, 200, with the interposition of a pair of guide plates 202c, the setting being such that the guide plates are advantageously horizontal. No modification of the flap tucking mechanism, as described in the specification No. 2,318,073, is necessary other than the re-arrangement of the operating levers and links required by the positions of the elements of the mechanism. In Figure 6, the parts of the flap tucking mechanism are identified by the reference numerals applied to the same parts in the drawings of the specification No. 2,318,073. The drive of the roller 243 supported by the brackets or frame plates 244 is effected from a gear wheel on the spindle of the roller 205 by way of the sequence of toothed wheels 224, 219, 220 and 221, and a wheel that is upon the spindle of the gear 246 driving a gear wheel on the spindle of the roller 243.

The rocking back fitting comprising the frame members represented by 226, and plates 228, 229, the distending mechanism comprising the lateral members represented by 250, and the distending arm 256 and also the brackets 233 and the bridge member 235 with the fingers 238 forming the support for the bottom of the envelope are substantially identical with the same parts of the construction described in the specification No. 2,318,073 and are merely turned as a group through 90°. The tucking fingers 278, 279 and the associated parts are disposed in the position necessary for co-operation with the remaining elements of the flap tucking mechanism. On completion of the tucking of the flap the envelope is discharged from the mechanism by the pressure exerted upon it by the rollers 236 and 243 in the manner hereinbefore described.

The flap tucking mechanism may, however, be set in any other suitable position so that the charged envelope passes therein in the vertical direction or at an angle. Similarly, the horizontal or angular disposition of the said mechanism may be employed in the construction of machine described in the specification No. 2,318,073.

I claim:

1. Apparatus for charging envelopes with postal matter and preparing them for despatch, comprising a filling table, feed mechanism adapted to feed towards the filling table the envelopes

with the flaps extended foremost, feed mechanism adapted to feed the postal matter towards the filling table, having the filling table spaced from the postal matter feed mechanism, a table-like element of a form and area to support the flap of the envelope and pivoted about an axis transverse to and spaced from the filling table, whereby the table-like element is adapted for movement from the envelope-receiving position in juxtaposition to the envelope feed mechanism and at the outer side of the filling table to a position in which it is aligned with the filling table in the space between the filling table and the postal matter feed mechanism, envelope flap gripper elements supported upon and cooperating with the table-like element and means for opening and closing the gripper elements when the table-like element is in the receiving position near to the envelope feed mechanism.

2. Apparatus for charging envelopes with postal matter and preparing them for despatch, according to claim 1, having the table-like element and the filling table of a cross-sectional shape in which the parts thereof on each side of a longitudinal middle line incline upwardly and outwardly.

3. Apparatus for charging envelopes with postal matter and preparing them for despatch, according to claim 1, having the table-like element and the filling table of a cross-sectional shape in which the parts thereof on each side of a longitudinal middle line incline upwardly and outwardly at an angle that increases from near the straight edge of the filling table in juxtaposition to the envelope feed mechanism.

4. Apparatus for charging envelopes with postal matter and preparing them for despatch, according to claim 1, having the table-like element formed along a longitudinal middle line with a shallow channel and the gripper elements supported by the table-like element provided to include an envelope distending element adapted to co-operate with the channel to flex the flap of and thus to distend an envelope engaged by the gripper elements upon the table-like element.

5. Apparatus for charging envelopes with postal matter and preparing them for despatch, according to claim 1, comprising postal matter guide fingers and a spindle supported at a distance from the table-like element, upon which the said fingers are rotatably mounted, the said fingers resting upon the outer sides of the envelope gripper elements and being moved by the gripper elements when they open and close and the spindle being spaced from the table-like element for the passage of the postal matter over the gripper elements and under the guide fingers.

6. Apparatus for charging envelopes with postal matter and preparing them for despatch, according to claim 1, comprising postal matter guide fingers, a spindle upon which the said fingers are rotatably mounted and links pivoted upon the table-like element and supporting the spindle so that the spindle is transverse to and spaced from the outer side of the table-like element and the said fingers are thereby adapted for a limited movement in the longitudinal direction of the table-like element.

7. Apparatus for charging envelopes with postal matter and preparing them for despatch according to claim 1, comprising postal matter guide fingers, a spindle upon which the said fingers are rotatably mounted, brackets upon the table-like element at the respective sides thereof, corresponding bell-crank levers pivoted upon the table-

like element, levers supporting the spindle and having their fulcra upon the bell-crank levers and links connecting the brackets with the said supporting levers, whereby a limited movement of rotation of the bell-crank levers effects a movement of the guide fingers in the longitudinal direction of the table-like element for the entry of the guide fingers into an envelope the flap of which is engaged by the gripper elements of the table-like element.

8. Apparatus for charging envelopes with postal matter and preparing them for despatch according to claim 1, comprising postal matter guide fingers, a spindle upon which the said fingers are rotatably mounted, brackets upon the table-like element at the respective sides thereof, corresponding bell-crank levers pivoted upon the table-like element, levers supporting the spindle and having their fulcra upon the bell-crank levers and links connecting the brackets with the said supporting levers, a spindle rotatably mounted parallel to the axis of rotation of the table-like element, crank arms upon the said spindle, coupling rods connecting the crank arms with the bell-crank levers, and a cam co-operating with one of the crank arms whereby a limited movement of rotation of the bell-crank levers effects a movement of the guide fingers in the longitudinal direction of the table-like element for the entry of the guide fingers into an envelope the flap of which is engaged by the gripper elements of the table-like element.

9. Apparatus for charging envelopes with postal matter and preparing them for despatch according to claim 1, having gripper elements and an envelope distending element of angular formation and formed with spindle-engaging parts and a spindle for supporting the gripper elements and the distending element at a position below the outer surface of the table-like element whereby the angular parts of the gripper elements and distending element extend around the outer edge of the table-like element and the gripper elements and distending element lie substantially parallel with the outer surface of the table-like element in the closed position.

10. Apparatus for charging envelopes with postal matter and preparing them for despatch according to claim 1, comprising gripper elements that are provided of angular formation and formed with recesses of rectangular cross-section to receive the spindle upon which they are mounted which spindle also has a rectangular cross-section, and locking elements for maintaining the gripper elements in position upon the spindle by engagement with slots formed in the walls of the recesses of the gripper elements that embrace the spindle.

11. Apparatus for charging envelopes with postal matter and preparing them for despatch

according to claim 1, having postal matter guide fingers provided with cylindrical supporting sockets, a spindle upon which the said guide fingers are rotatably supported, the said spindle slidably engaging the sockets of the guide fingers, and supporting levers for the guide finger spindle carried from the table-like element and formed with slot-like bearings for the reception of the ends of the spindle.

10 12. Apparatus for charging envelopes with postal matter and preparing them for despatch according to claim 1, provided with an envelope diverting member disposed in juxtaposition to the envelope feed mechanism and positioned to direct 15 a charged envelope moved from the filling table to a discharge mechanism, the said diverting element being pivotally mounted and a spring acting upon the diverting element to maintain it in the normal position, the said spring being overpowered by the table-like element when the latter is 20 in the position to receive an envelope from the feed mechanism and the diverting element is required to move from the normal position.

13. Apparatus for charging envelopes with postal matter and preparing them for despatch according to claim 1, having a postal matter register fitting comprising spaced pivoted supports disposed respectively at the sides of guides for the postal matter advancing to the filling table, 30 a feed roller positioned below the guides for the postal matter and carried by the supports forward of the pivotal axis and a transverse series of register fingers carried by the support forward of the feed roller for projection into the path of 35 the postal matter and a feed roller of fixed position co-operating with the feed roller upon the supports.

14. Apparatus for charging envelopes with postal matter and preparing them for despatch according to claim 1, having an envelope-diverting member disposed at a position at which an empty envelope is gripped by the gripper elements to the table-like element as it is advanced by the feed mechanism to the filling table, a spring acting upon the envelope diverting member to maintain it resiliently in a position to divert a charged envelope from the feed path, pairs of feed rollers receiving the charged envelope and a flap-tucking mechanism disposed to receive the charged envelope in a horizontal position from the pairs of feed rollers.
